UNITED STATES PATENT OFFICE.

DAVID A. GARVER AND CLARENCE H. STRAIGHT, OF BRYAN, OHIO.

TRAY FOR WHEELBARROWS.

SPECIFICATION forming part of Letters Patent No. 380,562, dated April 3, 1888.

Application filed December 14, 1887. Serial No. 257,923. (No model.)

To all whom it may concern:

Be it known that we, DAVID A. GARVER and CLARENCE H. STRAIGHT, citizens of the United States, residing at Bryan, in the county 5 of Williams and State of Ohio, have invented certain new and useful Improvements in Trays for Wheelbarrows; and we do hereby declare the following to be a full, clear, and exact description of the invention, such as will enable 10 others skilled in the art to which it appertains to make and use the same.

Our invention consists in making the sides and bottom of the tray in two parts, and in connecting said parts by strips of sheet metal, 15 which cover the joints and are secured at their edges to the two parts, the objects sought to be obtained being economy in material and in the labor of putting the parts together.

In the accompanying drawings, which illustrate our invention and form a part of this specification, Figures 1 and 2 represent, respectively, a top and bottom view of our tray complete; Fig. 3, an elevation of one of the sides, showing the sheet-metal connecting- 25 strip before its ends are bent over; and Fig. 4, a similar view showing the connecting-strips bent down. Figs. 5 and 6 are edge views of the bottom, showing the manner of putting the same together; and Fig. 7, an inner end 30 elevation of one of the sections of the tray, showing the manner of applying the connecting-strips.

A A' designate the bottom boards, which, as represented, are cut half the length of the 35 tray, and their inner or meeting ends are beveled to correspond with the angle formed by the double incline of the bottom, so as to make a close joint when the parts are put together. The bottom boards thus cut and 40 formed are placed together, as represented in Fig. 5, with the longer corners of their beveled ends abutting against each other, and are secured together by nailing over the joints thus formed a strip of sheet metal, a, the same 45 being nailed along its edges to both boards, as represented. The bottom boards thus united are brought to the position represented in Fig. 6, and by broken lines in Fig. 5, with their beveled edges in close contact and forming 50 a close joint.

The sides are formed of wedge-shaped boards B B', the lower edges being cut to correspond with the inclination of the bottom boards, and their inner or meeting edges being

beveled to correspond with the outward flare. 55 The upper outer corners are rounded, as usual. The sides thus formed are connected together, similarly to the bottom boards, by strips of sheet metal, b, which are nailed along their edges to both parts, covering the joint on the 60 outer side. The outer ends are then carried inward till their beveled edges are in close contact and form a close joint, and in this position they are ready to be nailed along their lower edges to the edges of the bottom boards. 65 The ends of the connecting-strips project past the edges of the side-boards, and are notched, as represented in Fig. 3, to enable them to be turned over said edges, the angle formed by bringing the boards into position preventing 70 them from being turned over otherwise, so as to make a smooth finish. The strip a is preferably of a length greater than the width of the bottom boards, A A', to allow its ends to overlap the edges of the side-boards, and to 75 be in turn overlapped by the ends of the strips b, as represented in Fig. 7. In this way the parts are securely bound together.

The construction above described enables us to utilize small pieces of lumber which 80 would be useless otherwise, and avoids the necessity of steaming and bending to bring the parts into shape. Moreover, it enables us to use inferior lumber, since the short lengths required can be cut out between knots 85 and other imperfections, thus materially cheapening the article.

Having thus described our invention, we claim as new—

1. The improved wheelbarrow-tray herein-before described, having its sides and ends made in half-lengths and united together by strips of sheet metal, which cover the joints and are nailed to both parts, substantially as and for the purposes set forth. 90

2. The improved wheelbarrow-tray herein-before described, the same being made in two independent transversely - divided sections, said sections being united by strips of sheet metal secured over the joint, substantially as 95 shown and described.

In testimony whereof we affix our signatures in presence of two witnesses.

DAVID A. GARVER.

CLARENCE H. STRAIGHT.
